CROSS FEED MECHANISM FOR SLICING MACHINES

Otto Theurer, Brooklyn, N. Y., assignor to Edward I. Friedman, New York, N. Y., and Harry Wiener, Brooklyn, N. Y.

Application June 12, 1936, Serial No. 84,808

2 Claims. (Cl. 146—102)

The present invention relates to automatic mechanisms whereby a member slidably mounted on a reciprocating carriage, is periodically advanced thereon, a predetermined distance transverse the line of travel of said carriage, and including means for effecting various adjustments, which mechanisms are particularly adaptable for embodiment in food slicing machines as the cross feed mechanism therefor, whereby the substance to be sliced is advanced beyond the plane of the knife, once per cycle of the reciprocating carriage which conveys the substance so that the knife enters the latter.

The principal object of this invention is to provide mechanisms of the type mentioned of novel and improved construction for periodically advancing the food substance beyond the plane of the knife, a distance equal to the thickness of the slice desired.

Another object is to provide a novel and improved mechanism of the character described, in which but a single adjustment will set the range of each advance and simultaneously correctly position a gauge plate which acts as a supporting wall for the substance sliced.

A further object is to provide a novel and improved mechanism carried and automatically operated upon the reciprocation of the carriage, whereby its motion on the carriage transverse the direction of travel of the carriage, will never be beyond a definite position, regardless of continued motion of the carriage. Embodying such in a slicing machine construction, the member on the carriage for advancing the food substance, will cease its movement on the carriage at a definite position before the plane of the knife, although there is further movement of the carriage.

Other objects and novel features of this invention will become manifest as the description proceeds.

In the accompanying drawings forming part of this application, similar characters of reference indicate corresponding parts in all the views.

Fig. 1 shows an elevation of a food slicing machine embodying the teachings of the present invention.

Fig. 2 is a fragmentary plan view thereof, partly in section, with platform removed, showing the reciprocating carriage and associated cross feed mechanism.

Fig. 3 is a fragmentary section taken along lines 3—3 in Fig. 2 showing the platform and components thereon.

Fig. 4 is a section taken at line 4—4 in Fig. 2

showing a fragmentary end view of Fig. 1 with the handwheel removed.

Fig. 5 is a fragmentary plan view of the adjustment means included in the mechanism.

Fig. 6 is a fragmentary plan view taken of Fig. 1 in the direction of lines 6—6.

Fig. 7 is a section taken at line 7—7 in Fig. 6.

Fig. 8 is a diagrammatic assembly view of components included in the means for periodically advancing the substance to be sliced toward the knife.

Fig. 9 is a sectional fragmentary view taken at line 9—9 in Fig. 6.

Fig. 10 is a fragmentary section taken at line 10—10 in Fig. 9.

In the drawings the numeral 15, is used to designate generally the frame of a slicing machine, and the numeral 16, a carriage frame slidably mounted thereon along the horizontal track members 17 and 18. Within the frame, is journaled 20 a horizontally positioned shaft 19, provided with a handwheel 20, at its forward end extending exteriorly of the frame, from which shaft, a crank means indicated generally by the numeral 21, is driven, whereby the carriage 16, is slid to and fro along its tracks 17 and 18. Also driven from said shaft 19, is the circular knife 24, by a system of sprockets 25 and 26, carrying the chain 27. This knife is rotatably mounted at one side of the frame 15, so that its plane is parallel to the line 30 of travel of the carriage 16.

The carriage 16, is provided with the fixed track members 28 and 29, intermediate and parallel to which is journaled the screw shaft 30, along which track members and screw shaft on 35 the carriage 16, a bracket 31, is mounted free to slide, which bracket carries a longitudinally 40 slideable pin 32, for engagement in the thread of the screw shaft 30. Such engagement is normally maintained by action of a coil spring 33, 45 encircling the pin 32, against a collar 34, fixedly mounted on said pin. It is evident that upon rotation of the screw shaft 30, the pin 32 in engagement therewith, will cause the bracket 31, to be slid across the carriage 16.

This bracket is provided with a pair of arms 35 and 36, extending normal thereto at its respective ends, for pivotally mounting the arms 37 at points 38, of a combined food clamp and shifter 39. A platform 40 is secured atop the carriage 16, on which is placed the substance 41 to be sliced. The bracket 31, lies beneath this platform 40, and is free to move on the carriage frame thereunder. The member 39, of course, moves along with the bracket 31, and is always 55

over the platform 40, where it is used to push the substance 41, across the carriage platform 40 towards the slicing knife 24, or else may be used to grip said substance by means of the teeth 39', and slidably shift said substance across the platform 40, pursuant to the intermittent advancing movement of the bracket 31. The face of member 39, is also provided with teeth elements 39'', or other suitable prongs to engage the substance 41, when said member is used merely as a pushing means as illustrated in Fig. 4 of the drawings.

Arm 36, has securely fixed thereto and upwardly extending therefrom, a handle member 42, while at arm 35, another handle member 43, is maintained free to pivot in ring 44. The lower end of this handle member 43, is pivotally linked by pin 45, to the extending end of shaft engagement pin 32, whereby upon movement of this handle towards its mate, said pin will become disengaged and said handles manually used to bring the cross feed means to initial position on the carriage.

A plate 46, for supporting the vertical surface 25 of the substance 41, while it is being sliced, has perpendicularly thereto a pair of forwardly extending rods 47 and 48, slidably mounted in the frame 15, whereby plate 46 presents a surface parallel to the plane of the knife edge, and forward thereof with respect to the line of motion of the carriage 16. The free end of rod 47, is provided with a thread groove 49, and carries thereon forward of the frame 15, a loosely mounted adjustment wheel 50, which wheel is journaled in the frame 15 by means of screw pin 51 which engages said wheel 50 within an annular groove 52 in the reduced end 53 thereof. A screw pin 54, through the wheel, is engaged in the groove 49. Upon manual rotation of the 30 adjustment wheel 50, the plate 46, will be moved towards or away from the plane of the knife 24. Another adjustment simultaneously effected upon movement of said wheel 50, will be later explained herein. An arm 55, pivotally secured at its lower 35 end on a stud screw 55', in the frame 15, extends upwardly, and is provided with a pin 56, which is in sliding engagement in the spiral groove 57, of a cam plate 58, which latter is secured by means of screws 59 to the face of 40 the adjustment wheel 50. It is evident that upon movement of this wheel, the arm 55 will be shifted to assume different positions with respect to the vertical, and the top end thereof fashioned as finger 60, will be at varied positions along the 45 path of travel of the carriage-conveyed rack member 61 and its downwardly projecting pin 62, in particular, with which it comes in contact during definite intervals while the carriage 16 reciprocates.

60 In a tubular structure 63, integral of the underside of the carriage 16, against the action of a coil spring 64 therein, is slidably mounted said rack member 61, having the pin 62 extending downwardly therefrom through a slot 65 in said structure; the line of movement, of which the rack 61 is capable, being parallel to the line of movement of the carriage 16, and the width of slot 65 being such, whereby the pin 62 therethrough prevents axial rotation of the rack member 61. A plug 66 closes 63, and acts as a stop for the spring 64.

The thread of the screw shaft 30, ends, to leave an unthreaded portion 30', whereby the engagement pin 32, will become automatically 75 disengaged from said shaft, and will lie against

said unthreaded portion, at which time, the bracket 31 and all it carries, will cease to move, even upon continued rotation of the screw shaft 30. Terminating the thread as at 30', in effect, provides a cam to effect disengagement of said 5 pin 32, whereby the cross feed bracket 31, will move no further towards the plane of the knife 24, although the remaining components of the machine continue in operation.

The other end of this shaft 30, is reduced, on 10 which reduced end 67, is fixed a clutch member 68, and a loosely carried complementary clutch member 69, which latter has fixed thereon a gear 70, and is slidably along the shaft end 67, against the action of a coil spring 71, positioned 15 about said shaft end and within a socket 72, in the carriage 16 therefor provided. The gear 70 is in constant engagement with the rack 61, and the action of spring 71 is to maintain the clutch members in engagement.

20 It is evident, that the further away the finger 60 is from the handwheel end of the machine, the greater will be the extent of turn of the screw shaft 30, and the incident advance of the cross feed member 39, on the platform 40, towards the 25 knife 24. Hence an adjustable means is provided for setting the thickness of slice desired. Also, the pitch of thread 49, is such, that upon any setting of the adjustment wheel 50, the plate 46 will lie beyond the plane of the knife 24, a 30 distance equal to the distance advanced by the cross-feed member 39, per cycle of the carriage 16. A pointer 73, fixed to the frame 15, indicates a reading on a scale graduated on the periphery of the adjustment wheel 50, of the 35 thickness of slice to be accomplished.

40 In operation, upon turning the handwheel 20, knife 24 will be rotated and the carriage 16 will be reciprocated. Each time the carriage will approach the handwheel end of the machine, finger 60 of the arm 55, will intercept the pin 62 whereby the rack member 61 will become fixed in space, and upon continued movement of the carriage 16, gear 70 will be turned a definite amount. The screw shaft 30 will likewise 45 be turned, for the clutch members 68 and 69, are designed to be in engagement, whereupon the member 39 engaging the substance 41, will advance across the carriage 16, a distance equal to the thickness of slice for which adjustment 50 had previously been made by an initial setting of the adjustment wheel 50. Upon reverse movement of the carriage 16, until pin 62 leaves the intercepting finger 60, the gear 70 will be 55 revolved in a direction opposite to that it had had at first. However, the clutch members 68 and 69 are so designed that their teeth 74 disengage upon rotation of the gear 70 in such reverse direction therefore, screw shaft 30 will receive no 60 rotary axial movement at this time.

65 As the cycle is repeated, the member 39, will be regularly advanced across the platform 40, until the pin 32 will become disengaged from the screw shaft 30. Thereafter, although the carriage 16 continues to reciprocate, and the screw 70 shaft 30 periodically turned, said member 39 will receive no further movement. Now, by means of the handles 42 and 43, said member 39 secured on the bracket 31, may be brought to initial operating position on the platform 40, and 75 the operation of the machine continued.

This invention is capable of numerous forms and various applications without departing from the essential features herein disclosed. It is therefore intended and desired that the embodiment

ment shown herein be deemed illustrative and not restrictive, and that the patent shall cover whatever features of patentable novelty exist in the invention disclosed; reference being had to the following claims, rather than to the specific description herein to indicate the scope of the invention.

I claim:

1. In a slicing machine having a frame, the combination of a slicing knife, means to convey the substance to be sliced into engagement with the knife, a shaft slidably mounted in the frame; said shaft being threaded at one end thereof, a plate secured at the other end of said shaft presenting a surface parallel to that of the slicing knife, adapted for support of the substance while it is sliced, means mounted on said conveying means, adapted when actuated to periodically shift the substance across the conveying means, an arm pivotally mounted on the frame adapted to intercept and operate the latter means prior to an engagement of the substance to be sliced with the knife, a wheel loose on said shaft at the threaded end thereof, journalled in the frame, a pin through the wheel in engagement with the thread in the shaft, a cam carried on said wheel, and a follower means connecting said frame and cam; the positioning of the plate and arm being such upon movement of the wheel, that the plate will be shifted to a position beyond the plane of the knife, a distance equal to the periodic advance of the substance across the conveying means effected by the attending change of position of the arm due to such movement of the wheel.
2. In a slicing machine having a frame, the combination of a slicing knife, a carriage slidably mounted on the frame, for conveying the substance to be sliced into engagement with the slicing knife, a bracket slidably mounted on the carriage for travel thereon transverse the path

of travel of said carriage, adapted to engage said substance, a screw shaft journalled on the carriage along a line parallel to the line of travel of the bracket, a pin slidably mounted on the bracket, in releasable engagement with the screw shaft in the thread thereof, a clutch member secured on said shaft, a complementary clutch member rotatably and slidably mounted on the shaft, means to maintain the clutch members normally in engagement, a gear securely mounted on the second clutch member; said clutch members being adapted to be in engagement upon rotation of the gear in one direction and to be disengaged upon reverse rotation of the gear, a rack slidably mounted on the bracket along a line parallel to the path of travel of the carriage; said rack and gear being in constant engagement, means to normally maintain said rack at a definite position on the bracket, an element extending from the rack, an arm movably mounted on the frame, extending in the path of said element and adapted to intercept same prior to an engagement of the substance to be sliced and the knife, a shaft slidably mounted in the frame; said shaft being threaded at one end thereof, a plate secured at the other end of said shaft presenting a surface parallel to that of the slicing knife, adapted for support of the substance while it is sliced, a wheel loose on said shaft at the threaded end thereof, journalled in the frame, a pin through the wheel in engagement with the thread in the shaft, a cam carried on said wheel, and a follower means connecting said frame and cam; the positioning of the plate and arm being such upon movement of the wheel, that the plate will be shifted to a position beyond the plane of the knife, a distance equal to the periodic advance of the bracket effected by the attending change of position of the arm due to such movement of the wheel.

OTTO THEURER.
